Primary Examiner — Freda S Nunn(74) *Attorney, Agent, or Firm* — Patent Capital Group(57) **CLAIM**

The ornamental design for an electronic device with a window, as shown and described.

DESCRIPTION

FIG. 1 is a front view of an electronic device with a window showing our new design;

FIG. 2 is a perspective view thereof; and,

FIG. 3 is another perspective view thereof.

Broken lines shown in the drawings illustrate portions of the electronic device, and form no part of the claimed design.
